UNITED STATES PATENT OFFICE.

WILLIAM L. FUSSELL, OF PHILADELPHIA, PENNSYLVANIA.

UMBRELLA AND PARASOL.

SPECIFICATION forming part of Letters Patent No. 288,566, dated November 13, 1883.

Application filed September 3, 1883. (No model.)

To all whom it may concern:

Be it known that I, WILLIAM L. FUSSELL, a resident of Philadelphia, Pennsylvania, and a citizen of the United States, have invented 5 certain Improvements in Umbrellas and Parasols, of which the following is a specification.

The object of my invention is to so construct an umbrella or parasol that, when closed, it will present a neater and more compact appearance than usual; and this object I attain in the manner hereinafter set forth, reference being had to the accompanying drawings, in which—

Figure 1 is a sectional view of the upper 15 portion of an umbrella or parasol made in accordance with my invention, and Figs. 2, 3, 4, and 5 side views of parts of the same.

A is the stick, which is in the present instance tubular, and has a tubular metallic core, 20 B, for the purpose of strengthening the same. The upper end of the stick is reduced in diameter, as shown at a, Fig. 5, for the reception of the notch D, to which the ribs F are hung, as usual, the notch being smaller in diameter than an 25 ordinary notch, which is fitted directly over the stick. This renders the umbrella or parasol very compact when closed; but in order to enhance this appearance of compactness, I make the tip G larger in diameter than the 30 stick A, the tip being, in fact, about equal in diameter to the body of the umbrella or parasol when the latter is closed.

The cover x is secured by the usual cap, b, and the tip G, which slips over a projecting

portion of the central core, B, of the stick, has 35 a ferrule, d, fitting snugly to the cap, as shown in Fig. 1, so that the upper portion of the umbrella or parasol presents an appearance of substantially uniform diameter, there being no increase in size where the tip joins the 40 body.

In order to strengthen the stick at and near the joint with the tip, I provide the tubular core with a central rod, f, which may be of wood or metal, this rod fitting snugly to the 45 core, and being further held by the pin which secures the notch.

The main feature of my invention, however—that is to say, the enlarged tip G—may be employed in connection with a solid stick, 50 if desired.

I claim as my invention—

1. The combination of the notch D, the stick A, reduced in diameter at the end for the reception of the notch, and the tip G, larger in 55 diameter than the stick, as set forth.

2. The combination of the stick A, having a reduced portion, a, and tubular metallic core B, the notch D, the tip G, and the strengthening-rod f, as set forth.

In testimony whereof I have signed my name to this specification in the presence of two subscribing witnesses.

WILLIAM L. FUSSELL.
